WELL HEAD

Ernest L. Barker, Houston, Tex.

Application September 12, 1936, Serial No. 100,409

6 Claims. (Cl. 285—22)

This invention relates to a well head and has particular relation to novel means for forming a fluid tight joint between the casing head and hanger as well as between the head and hanger assembly and the Christmas tree adapter which supports the Christmas tree on the head.

It is an object of the invention to provide a casing head having a hanger seat therein with a hanger on the seat and an adapter on the head and a novel type of seal ring bridging the joint between the hanger and the head and forming a fluid tight joint with the adapter.

It is another object of the invention to provide a well head with means for sealing all of the joints between the casing head and hanger as well as between the head and hanger assembly and the Christmas tree adapter. With the above and other objects in view the invention has particular relation to certain novel figures of construction, arrangement of parts and use, examples of which are given in this specification and illustrated in the accompanying drawing wherein:—

Figure 1 shows a side elevation of the head.
Figure 2 shows a vertical sectional view thereof, and

Figure 3 shows a vertical sectional view illustrating a modified form of the head.

Referring more particularly to the drawing wherein like numerals of reference designate the same parts in each of the figures, the numeral 1 designates a casing head having an inside downwardly tapering seat 2.

Numerals 3 designates a tubular hanger whose upper end is flared to conform to the shape of and to closely fit the seat 2.

The head is adapted to be connected to the upper end of the well casing 4 and the lower end of the hanger is threaded for connection to the upper end of the well tubing 5 which is suspended from the hanger.

The upper end of the hanger is approximately flush with the upper end of the head and said upper ends have the respective annular grooves 6 and 7 on opposite sides of the joint between the hanger and head.

The upper end of the head has an annular outwardly extending flange 8 and aligned above this flange there is a similar outwardly extended flange 9 of the Christmas tree adapter 10 to which a conventional Christmas tree 11, or other flow pipe may be connected. The underside of the Christmas tree adapter is provided with an annular groove 12.

There is a seal ring 13 whose upper end terminates in an annular apex 14 which is seated in the groove 12. The lower end of the seal ring 13 is formed with the annular inner and outer legs 15, 16, which are seated in the respective grooves 5 and 7, whereby the joint between the hanger and head is broken.

The flanges 8 and 9 are secured together by means of the bolts 17 which pass therethrough.

In the form shown in Figure 3 the casing head 1a has a downwardly tapering seat 2a but its inner wall, above and beneath said seat is approximately cylindrical. In this form the hanger 3a is externally shaped to conform to the shape of and to fit closely within the head and to be supported on the seat 2a and is provided to support the wall tubing 5.

In this form the upper end of the hanger 3a has two grooves 6 and the upper end of the head has two grooves 7, said pairs of grooves 6 and 7 being annular and arranged on opposite sides of the joint between the hanger and head. In this type of well head the Christmas tree adapter 10 is employed and is secured on the head 1a in the same manner as shown in Figures 1 and 2. The underside of the adapter of this form has two annular grooves 12 and the seal ring 13 has two upper apexes or legs which fit in grooves 12 and two pairs of depending legs 15 and 16 which fit in the corresponding pair of grooves 6 and 7 thus forming a very effective seal for the joints of the well head assembly.

The drawing and description disclose what are now considered to be preferred forms of the invention by way of illustration only while the broad principle of the invention will be defined by the appended claims.

What I claim is:

1. A well head comprising a casing head having an inside seat, a tubing hanger on the seat, the upper end of the head and hanger assembly having annular grooves one on each side of the joint between the hanger and head, a Christmas tree adapter secured to the head and having an annular groove in its lower end and a single seal ring having an upper edge seated in the groove in the adapter and a pair of lower legs with edges seating in the grooves in the head and hanger respectively.

2. A well head comprising a casing head adapted for connection to a casing in a well, a tubing hanger seated in the head, said head and hanger each having a groove around its upper end, a seal ring having annular depending legs seated in

45

said grooves, and an adapter secured on the head and having a groove around its lower end in which the seal ring is also seated.

3. A well head comprising a casing head adapted to be connected to a casing in a well having a plurality of grooves around its upper end, a tubing hanger seated in the head and having a plurality of grooves around its upper end, a seal ring having depending legs seated in the respective 10 grooves, a flow line connection secured on the casing head and having a groove around its lower end in which the seal ring is also seated.

4. A well head comprising a casing head adapted to be connected to the upper end of a well casing, 15 a tubing hanger seated in the head, the head and hanger each having a plurality of annular grooves at their upper ends, a seal ring having depending legs seated in said grooves, a flow line connection on the casing head having a plurality of grooves 20 around its lower end said seal ring having annu-

lar upstanding legs seated in the grooves of said connection.

5. A well head comprising a casing head, a tubing hanger therein, an adapter clamped on the casing head, and a single three-point seal ring clamped between the adapter and the head and hanger, the ring having a top edge which seals against the adapter and a pair of bottom edges one of which seals against the casing head and the other of which seals against the hanger. 10

6. A well head comprising a casing head, a tubing hanger seated therein, a flow line clamping member clamped to the casing head, and a single seal ring between the clamping member and the head and hanger, the seal ring bridging 15 the joint between the head and the hanger and having spaced legs which engage the head and hanger respectively and an upper edge which is engaged by said clamping member.
